PIPE WRAPPING MACHINE

Dozier Finley, Berkeley, Calif., assignor to The Paraffine Companies, Inc., San Francisco, Calif., a corporation of Delaware

Application January 30, 1931, Serial No. 512,346

13 Claims. (Cl. 242—11)

My invention broadly relates to a machine for wrapping objects, and more particularly to a pipe wrapping machine and to the pipe moving means and wrapping strip applying mechanism thereof.

5 It is among the objects of my invention to provide a wrapping machine with which pipes may be wrapped with a plurality of helically and longitudinally applied strips; the helically applied strips being wound in either the same or

10 in opposite directions.

Another object of my invention is to provide a pipe wrapping machine embodying improved means for handling the pipes, so that the wrapping may be carried on as a substantially continuous operation without having to couple the

15 pipes together.

Another object of my invention is to provide improved means for transferring the wrapping material from supply rolls to the pipe, including the provision of means for permitting substantially a 90° variation in the pitch of the helically applied wrappings; and of means for varying the degree of overlap in the helical wrapping at any given pitch.

20 Further objects of my invention include the provision of a pipe wrapping machine in which the adhesive fluid is applied to the pipe without waste; in which the pipes are handled without scarring or otherwise damaging the pipe or its 25 priming coat; and in which pipes of any description, such as riveted pipes, thin walled pipes and the like, may be wrapped.

The invention possesses numerous other objects and features of advantage, some of which, 30 with the foregoing, will be set forth in the following description of my invention. It is to be understood that I do not limit myself to this disclosure of species of my invention, as I may adopt variant embodiments thereof within the 35 scope of the claims.

40 Referring to the drawings:

Figure 1 is side view, partly in elevation but largely in vertical section, of the pipe wrapping machine embodying my invention, showing the 45 left hand portion of the machine; and

Figure 2 is a similar view showing the right hand portion of the machine.

Figure 3 is transverse vertical sectional view 50 of the machine taken in a plane indicated by the line 3—3 of Figure 2, and shows the wrapping rotor in end elevation; portions of the rotor assembly are shown in vertical section to more clearly disclose the construction.

Figure 4 is a transverse vertical sectional view

showing the pipe moving means, taken in a plane indicated by the line 4—4 of Figure 1.

In terms of broad inclusion, the pipe wrapping machine embodying my invention comprises means for holding the wrapping material in a roll encircling and coaxial with the pipe. Guide means are provided for directing the wrapping material from the roll to the pipe. Means are provided for moving the pipe past the roll, and means are provided for moving the guide means about the pipe to transfer the wrapping material from the roll to the pipe and apply the material in a helical wrapping.

5 Means are provided for adjusting the guide means to vary the pitch of the helical wrapping, and means are also provided for varying the relative movements of the pipe and the guide means to alter the degree of overlap between adjacent turns in the wrapping. A plurality of secondary rolls of wrapping material are preferably provided, and are circumferentially journaled about the pipe adjacent the rotor. Guide means are provided for directing the strips from the secondary rolls so that they are applied longitudinally of the pipe with edges abutting. These longitudinally applied strips are preferably placed over the first helical wrapping.

10 A second helical wrapping, preferably wound in a direction opposite to that of the first helical wrapping, is applied over the longitudinal strips; the second helical wrapping being applied by means similar to that employed for the first wrapping. Means are also provided for applying an adhesive fluid to the pipe, and means are provided for conserving excess amounts of the fluid, so that waste in the application thereof is prevented.

15 In greater detail, the wrapping machine embodying my invention comprises a frame 2 mounted on a suitable foundation 3. The frame 2 is in the form of a housing providing a passageway for the pipe 4 to be wrapped. The pipe is supported at one end by the pipe moving means generally designated 6, and at the other end by a set of holding rollers 7 circumferentially disposed about the pipe and journaled in a suitable supporting bracket 8. Several sets of these holding rollers are preferably arranged further along the pipe, so that the pipe will be firmly supported after it leaves the moving means 6. A suitable conveyor system may be provided to take care of the wrapped pipes after they leave the machine.

20 Referring particularly to Figures 1 and 4, the pipe moving means preferably comprises a plurality of endless belts 9, two being shown, run-

25 55

ning longitudinally of the pipe; one being positioned below the pipe, and the other above it. These drive belts are carried by the spaced pulleys 11 having the flanged edges 12 for holding the belts in position. The pulley shafts 13 are journaled in suitable bearing blocks 14 supported on the ends of the rods 16; the rods in turn being slidably mounted in the frame 2.

A cross bar 17 is slidably mounted on the supporting rods 16 adjacent each of the pulley shafts 13, and is adjustably positioned by a hand wheel 18 working thru a screw 19 threaded in the frame 2. A coil spring 21 is positioned about each of the supporting rods 16, and is compressed between the bearing block 14 and the end of the cross bar 17. By this arrangement it is apparent that the belts 9 may be moved to and from each other to accommodate various sizes of pipe; the supporting rod nuts 22 serving to adjustably limit the inward movement of the belts to accord with a given pipe diameter.

After being positioned against a pipe the belts are resiliently held thereagainst by the springs 21, and by turning the hand wheels 18 this pressure may readily be varied. In order to enhance the tractional engagement between the drive belts and the pipe a series of recessed cleats 23 are preferably provided, and are secured in spaced position along the belts. The cleat recesses 24 are cut to accord with a given pipe circumference, and belts with cleats having different shaped recesses are preferably provided to accord with different sizes of pipe.

The reach of the belt which engages the pipe is supported between the pulleys 11 to further enhance the tractional engagement between the belt and the pipe. This is preferably accomplished by a plurality of rollers 26, three being shown, journaled in a yoke frame 27 mounted on a shaft 28. This yoke shaft is mounted in a manner similar to pulley shafts 13 of the belt mounting, and will not be described in detail; suffice to say that when the hand wheel 18 is turned the pressure on the supporting rolls 26, and consequently the reach of the belt, is varied.

The drive for the belts 9 is generally best shown in Figure 1; certain details being better shown in Figure 4. A synchronous motor 29 serves as a prime mover, and is connected to a frame journaled drive shaft 31 thru the spur gears 32. A vertical shaft 33 is also journaled in the frame 2, and is arranged adjacent the end of a pulley shaft 13 of each belt; the shaft 33 being connected with the drive shaft 31 thru the miter gears 34.

Drive from the vertical shaft 33 to the pulley shafts 13 is effected by the gear boxes 36, whereby a suitable worm slideable on the vertical shaft meshes with a worm gear 37 mounted on the end of the pulley shaft. This arrangement completes the drive from the motor 29 to the belts 9, and at the same time allows the belts to be moved relative to the pipe. By replacing the gears 32 for others having a different ratio an operator may change the rate at which the pipe is moved.

Means are provided for carrying the pipes to be wrapped to the machine and into engagement with the drive belts 9 of the pipe moving means. A conveyor is arranged along the extended longitudinal axis of the machine and comprises an endless chain 38 running in the channels 39 held by a suitable support 41 and over a sprocket 42 journaled on the frame 2 adjacent the lower drive belt 9. The conveyor

chain sprocket 42 is driven from the drive shaft 31 thru a suitable reduction gearing 43, and a slip belt 44 running over a pulley 46 mounted on the sprocket shaft 47. A spring pressed idler pulley 48 running against the slip belt 44 serves to tension the belt to effect the drive.

Suitable guide rollers 49 arranged along the conveyor chain 38 and journaled on the support arms 51 are provided for guiding the pipe as it is carried along by the conveyor and for directing it into engagement with the drive belts 9 of the pipe moving means. A slotted lug 52 is slipped over a pair of link pins in the conveyor chain 38 behind the pipe, and serves to push the pipe along. When the pipe leaves the end of the conveyor the lug 52 continues along and drops out of engagement with the chain as it is carried over the sprocket 42.

The drive to the conveyor chain 38 is adjusted so that the chain moves slightly faster than the drive belts 9 of the pipe moving means. Due to the presence of the slip belt 44, however, the pipe is merely fed to the pipe moving means; further movement of the pipe being effected entirely by the drive belts 9. By this arrangement it is apparent that pipes are continually fed to the machine, and that a new pipe to be wrapped is always ready to take the place of one being wrapped in the machine. When a pipe passes out of engagement with the drive belts 9 the next succeeding pipe serves to push it on thru the machine.

Means are provided for applying a strip of wrapping material to the pipe in a helical wrapping. Arranged on the frame 2 ahead of the pipe moving means and journaled on a hollow frame bearing 53 coaxial with the pipe 4 is a rotor 54 having the gear teeth 56 cut in its periphery. An annular plate 57 is secured to the end of the bearing 53 by the screws 58, and bears against the side of the rotor 54 to hold it in its journaled position.

The rotor is rotated by a frame journaled shaft 59 thru a pinion 61 meshing with the rotor teeth 56. The shaft 59 is connected to the drive shaft 31 thru a chain drive 62. A suitable speed change gearing 63, of any conventional construction, is interposed in the drive shaft 31 adjacent the chain drive 62, so that the rotation of the shaft 59, and consequently the rotor 54, may be varied.

Means are provided on the rotor 54 for holding the wrapping material in a roll 64 encircling and coaxial with the pipe 4. A pair of annular plates 66, held spaced by the tie rods 67, are secured to the rotor 54 by bolt ends 68 of the tie rods 67. A plurality of loosely journaled rollers 69 are journaled in the annular plates 66, so that they are circumferentially disposed about the pipe 4. A pair of spaced annular plates 71 are journaled on the rollers 69 in the roller grooves 72. This arrangement provides a reel adapted to hold the roll 64 of wrapping material; the rollers 69 providing the core of the reel, and the annular plates 71 providing the flanges. Since the core rollers 69 and flange plates 71 are all loosely journaled, the roll 64 of wrapping material is free to slip around on the reel.

Guide means are provided for directing the wrapping material to the pipe 4, so that strip material 73 is taken off the inside of the roll 64 and applied on the pipe in a helical wrapping. Referring particularly to Figures 2 and 3, a guide roller 74 is arranged between the reel rollers 69 and the pipe 4. One end of the guide

5 roller shaft 76 is pivotally mounted on a bracket 77 secured to the inner annular plate 66 of the reel mounting; the pivot being effected by a ball and socket joint 78. The other end of the guide 5 roller shaft 76 is slidably mounted on a bracket arm 79 in a pivoted bearing 81.

As the rotor 54 rotates the guide roller 74 is carried around the pipe 4. As a result, the strip material 73 is pulled out from the inside 10 of the roll 64 and thence directed to the pipe at an angle depending upon the angular position of the guide roller. Means are provided for adjusting the guide roller 74 to change its position relative to the pipe. A ring 82 having 15 gear teeth 83 cut in its periphery is journaled on the outer annular plate 66 of the reel mounting on the grooved plate journaled rollers 84. This ring carries the bracket arm 79 which supports the outer end of the guide roller.

20 The ring 82 is rotated by a pinion 86 which meshes with the ring teeth 83 and is journaled about the shaft 59 in a frame mounted bearing bracket 87. A sleeve 88 is slidably mounted for rotation with the shaft 59, and is provided 25 with a helical key 89 engaging a complementary keyway in the pinion 86. The shaft 59 is journaled in the arms of a yoke 90 slidably mounted in a suitable slideway 91 in the frame 2, and the sleeve 88 is confined between the yoke arms. 30 A hand wheel 92, working thru a screw 93 which is journaled in the frame 2 and threaded in the yoke 90, provides means for adjustably moving the yoke.

25 The diameters of the rotor 54 and ring 82 are the same, and each is driven by the same shaft thru pinions of the same diameter. Consequently, when the shaft 59 revolves the rotor 54 and ring 82 are rotated at the same speed. As a result, the angular position of the guide roller 74 remains fixed relative to the pipe. When the yoke 40 adjusting hand wheel 92 is turned, however, the ring 82 is rotated relative to the rotor 54, and the angular position of the guide roller is changed.

45 Means are preferably provided for applying a layer of wrapping material over the helical wrapping. A secondary frame 94 is mounted on the foundation 3 ahead of the frame 2. A plurality of arms 96 are provided on the frame 94, 50 and are arranged to hold a plurality of secondary rolls 97 of wrapping material; four of these rolls are shown circumferentially journaled about the pipe.

An adjustable spring pressed guide roller 98 55 having a concave surface complementary to the pipe surface is mounted on each of the roll supporting arms 96. These guide rollers are proportioned so that their concave faces cooperate to provide a bearing surface completely 60 surrounding the pipe. Rollers having different curvatures are provided to accord with different sized pipes. The wrapping strip 99 is peeled off the secondary rolls 97 and is applied longitudinally of the pipe by the guide rollers 98 as the pipe 65 moves thru the machine. The width of the wrapping strip 99 is substantially equal to the width of the guide rollers, so that the edges of the applied strips abut to form a substantially continuous layer about the pipe. Obviously, by 70 using a wider wrapping strip the edges of the applied strips may be made to overlap.

An auxiliary winding means is provided ahead of the secondary rolls 97 for applying a helical wrapping over the longitudinally applied strips. 75 This winding means is similar to the winding

means described in connection with the first applied wrapping; and where duplications in construction exist, these elements are similarly designated. The drive for the auxiliary winding means, however, is shown as a separate unit, 5 and comprises a synchronous motor 100 connected to the rotor drive shaft 101 thru a suitable speed change gearing 102, a speed reduction 103 and a chain drive 104. The motors 29 and 100 are run in synchronism to maintain a constant 10 relation between the speeds of the two drives. While two independent drives are shown, it is to be noted that a single prime mover may be used to drive the entire mechanism.

The rotor in the auxiliary winding means is 15 preferably rotated in a direction opposite to that of the rotor in the winding means first described, so that the strip material 105 is applied over the transversely applied strips 99 in a helical wrapping wound in a direction opposite to that of the first helical winding. It is to be noted, however, that the two helical wrappings may be wound in the same direction by merely reversing the direction of rotation of one of the rotors. For the purposes of illustration a reversing mechanism 106 is shown interposed in the drive to the 20 rotor 54.

25 It is further to be noted that other combinations of wrapping may be made. By leaving out the first helical winding a two layer covering may 30 be obtained; the longitudinal strips being applied directly to the pipe and then covered with the final helical wrapping. If desired, the longitudinally applied strips may be omitted, and a covering 35 obtained comprising two layers of spiral wrapping, either wound in the same or in opposite directions. By adding other wrapping units, or by running the pipe thru the machine again, an additional number of layers may be 40 applied.

45 Means are provided for applying an adhesive waterproof fluid to the pipe. Preferably, a cylindrical jacket 107 is arranged to receive the pipe 4 prior to the wrapping. The jacket is held substantially coaxial with the pipe by the adjustable spring pressed supporting rollers 108 adapted to run on the pipe. One of these rollers is mounted outside at the rear of the jacket, and the other roller is mounted inside adjacent the head end of the jacket. 50

55 A conical wiping head 109 of spring steel or other resilient material, and having a series of slits 111 cut in its converging edge, is mounted on each end of the jacket 107. These wiping heads are arranged so that their converging edges are headed in the direction of the pipe movement. The heads are reinforced by the conical backing plates 112 and are secured in place on the jacket by the screws 113. A tank 114 is mounted on the frame 2 for holding a supply of the waterproof 60 cementing fluid 116, which may conveniently be a bituminous material. Suitable heating elements 117 are preferably mounted in the tank for heating the fluid.

65 A pipe 118, preferably covered by a strainer 119, leads out from the tank bottom, and connects with a suitable gear pump 121. A pipe 122 leads from the other end of the pump and discharges into a sump 123. A flexible duct 124 is connected with the pipe 122, and opens into 70 the bottom of the jacket 107. A similar duct 126 leads from the top of the jacket 107, and connects with a pipe 127 which passes up thru the tank fluid 116 and is capped by a distributor head 128. 75

A butterfly valve 129 is journaled in the discharge pipe 122 below the duct 124, and a rocker arm 131 is mounted on its shaft 132. One end of the rocker arm 131 is connected thru the linkage 133 to a clutch 134 for connecting and disconnecting the pump 121; the clutch being interposed between the pump shaft 136 and its chain drive 137 from the shaft 59. The linkage 133 is arranged so that the pump is connected when the butterfly valve is closed, and disconnected when the valve is open.

The other end of the rocker arm 131 is connected by a rod 138 and thru a compression spring 139 to the downwardly projecting arm of a bell crank 141 journaled on the conveyor sprocket shaft 41. A spring 142 acting on the lower end of the bell crank arm tends to urge the butterfly valve open. The other arm of the bell crank 141 is provided with a roller 143 adapted to run on the lower side of the pipe to hold the crank arm down and the butterfly valve closed.

By this arrangement the pump 121 is kept running and the butterfly valve is kept closed while a pipe is in the machine. The fluid is continuously circulated thru the jacket 107 and distributed back over the surface of the fluid in the tank to be reheated. When the last pipe passes thru the machine the bell crank 141 is released, consequently, the pump is automatically stopped and the butterfly valve is opened to permit the jacket and communicating ducts to drain into the sump 123 before any of it has an opportunity to spill out of the jacket.

The wiping heads 109 are constructed to make a sliding fit with the pipe, so that the fluid will be prevented from escaping past the rear wiping head at all times, and from past the forward wiping head when the pipe is stationary. When the pipe is moved, however, the flooded pipe passes out of the forward end of the jacket with an evenly deposited coating of the fluid; it being noted that excess amounts of the fluid are conserved, and that the fluid is applied without waste. Wiping heads having different sized apertures are provided for accommodating pipes of different sizes.

It is also preferred to provide a heater coil 144 around the fluid jacket 107 for assisting in maintaining the fluid at the proper temperature. This heater may be an ordinary resistance coil, or it may be in the nature of a primary winding for an alternating current. In the latter case the jacket 107 would act as a short circuited secondary to provide the required heat.

Preferably, means are provided for applying a cementing fluid to secure the longitudinal applied strips to the first helically applied strip. For this purpose a tubular ring 146 is preferably disposed about the pipe 4 adjacent the supply rolls 97. This ring is preferably mounted on suitable supports 147 secured to the brackets 96. A duct 148 communicates between the tank 114 and ring 146, and a suitable pump 149 interposed in the duct 148 is preferably provided for supplying the fluid to the ring under pressure. Any suitable means may be employed for driving the pump.

A plurality of discharge nozzles 151 are provided on the ring 146 to direct the fluid between the longitudinally applied strips 99 and the helical wrapping. Since the pipe 4 is moving forward, the fluid is immediately covered by the strips 99, so that little if any of the fluid is lost. If desirable, a fluid may also be applied to bind the final helically applied strip 105 to the lon-

gitudinally applied strips 99. For this purpose a fluid applying means, preferably similar to that described for applying the fluid to the pipe, may be employed. In this case the supporting arms 96 would be lengthened and the jacket 107 disposed about the pipe between the guide rollers 98 and bearing 94. Of course the wiping heads 109 would be designed to accord with the increased diameter due to the overlying wrappings. This apparatus is not shown because it would be substantially a duplicate of what has already been described in detail.

Operation.—An operator adjusts the speed of the rotors 54 relative to the pipe 4 to give the desired overlap to the helical wrapping; and then sets the guide rollers 74 to direct the strip materials 73 and 105 to the pipe at the desired angles, depending upon the pitches to be given the helical wrappings. The machine is then started. As the pipe 4 passes into engagement with the drive belts 9 the bell crank 141 is moved down to close the butterfly valve 129 and start the pump 121; the pump action being sufficiently slow to allow the pipe to move thru the jacket before the fluid spills over the lower edges of the wiping heads. The pipe is now moved forward thru the fluid jacket 107 by the pipe moving means or drive belts 9. As the pipe is moved by the belts 9 the action of the slip belt 44 permits the conveyor chain 38 to slow down to accord with the pipe movement. When a pipe passes out of engagement with the conveyor chain, however, the conveyor immediately speeds up to bring up a new pipe against it.

When the pipe reaches the inside of the first rotor 54 the machine is stopped and the strip 73 is threaded thru the bottom of the reel and around the guide roller 74, after which it is given a turn about the pipe at the selected pitch and overlap and secured by any suitable means. The pipe is then permitted to move ahead to the guide rollers 98, at which point the strips 99 from the secondary rolls 97 are started on the pipe under the pressure guide rollers and secured in place by any suitable means.

Again the pipe is allowed to move, this time with the fluid pump 149 operating, until the pipe reaches the inside of the rotor 54 of the auxiliary wrapping means. At this point the wrapping strip 105 is threaded thru the reel and over the guide roller 47, after which it is given a turn about the pipe at the selected pitch and overlap and secured by any suitable means. The machine together with the fluid pump 149 is now started again and allowed to continue as long as pipes are to be wrapped; the conveyor chain 39 serving to abut a new pipe against the one being wrapped after it leaves the conveyor. After the wrapped pipes leave the machine the wrapping connecting them may be cut by any suitable means. The last pipe thru the machine is a dummy, and merely serves to push the last wrapped pipe on thru the machine.

The simple longitudinal motion of the pipe thru the machine, together with the improved means by which this motion is effected, are important features of my invention. It is to be noted that the drive belts 9 engage a substantial portion of the pipe surface, and impart movement to the pipe without placing an undue strain on the pipe, and without scratching or otherwise injuring its surface or priming coat. Non-circular, riveted, lock bar and other special pipes may readily be wrapped in the machine. Furthermore, the machine will wrap thin walled

pipes which would collapse in the machines used at the present time.

In connection with special exceedingly thin walled pipes, it may be desirable to give added support to the pipe walls adjacent the pipe moving means. This may be accomplished by inserting a suitable sliding block 151 in the pipe between the drive belts 9. An anchor line 152 is preferably provided for holding the block 156 in position. This arrangement is indicated by dotted lines in Figure 1.

Another important feature of my invention resides in the mounting of the guide roller 74 for directing the helically applied wrapping strip. This roller is adjustable to apply the wrapping strip at all pitches, from the narrowest possible angle to the largest; in other words, the guide roller will describe a 90° change of position in the direction of feed of the strip to the pipe. In other words, if desired, either or both of rotors 54 could be held against movement and the guide rollers 74 set so that the material is merely pulled off the reels and applied to the pipe as a longitudinal wrapping. With this in mind any combination of longitudinal and helical wrappings could be applied merely by a plurality of the units described as the helical wrapping means. In addition, the guide roller may be adjusted during the wrapping operation to make corrections in the wrapping pitch.

Further advantages of the machine become apparent when it is realized that couplings for connecting the pipes together to make the wrapping operation continuous are unnecessary; that various combinations of wrapping may be obtained; and that the fluid applying means deposits an even coating of the fluid on the pipe without waste.

I claim:

1. In a pipe wrapping machine, a rotor, means arranged on the rotor for holding a supply of wrapping material, a ring journaled on the rotor, a guide roller pivotally mounted on the rotor and ring for directing the material from the supply to the pipe, means for rotating the ring relative to the rotor for adjustably fixing the guide roller with respect to the pipe to determine the angle at which the wrapping material passes to the pipe, and means for rotating the rotor and ring at the same speed to transfer the wrapping material from the supply to the pipe.

2. A pipe wrapping machine comprising means for holding supply rolls of wrapping strip, means for moving the pipe longitudinally past the supply rolls, means for applying a strip to the pipe in a helical wrapping, means for applying a strip longitudinally of the pipe and over said wrapping, means for applying a strip to the pipe in a helical wrapping and over the longitudinally applied strip, and means for applying a fluid to seal the longitudinally applied strip between said helical wrapping.

3. A pipe wrapping machine comprising means for holding supply rolls of wrapping strip, means for moving the pipe longitudinally past the supply rolls, means for applying a strip to the pipe in a helical wrapping, means for applying a strip longitudinally of the pipe and over said wrapping, means for applying a strip to the pipe in a helical wrapping and over the longitudinally applied strip, said last mentioned wrapping being applied

in a direction opposite to that of the first mentioned wrapping, and means for applying a fluid to seal the longitudinally applied strip between said helical wrapping.

4. The combination with a pipe wrapping machine having means engaging the periphery of the pipe for effecting its movement, of a support slidably within the pipe, and holding means for positioning the support adjacent the pipe moving means.

5. A pipe wrapping machine comprising means for holding supply rolls of wrapping strip, means for applying fluid to the pipe, means for applying a strip to the pipe in a helical wrapping, means for applying fluid over said wrapping, means for applying a strip longitudinally of the pipe and over said wrapping, and means for applying a strip to the pipe in a helical wrapping and over the longitudinally applied strip.

6. A wrapping machine comprising a rotor for carrying a supply roll of wrapping material, a guide roller adjustably mounted on said rotor and over which the material is adapted to pass, and means for adjusting the position of said roller while the rotor is rotating.

7. In a pipe wrapping machine, a driving head for receiving the pipe and advancing the same through the machine, means for feeding pipe to the driving head, means for actuating the feeding means, and a slip drive interposed in said actuating means.

8. In a pipe wrapping machine, a driving head for receiving the pipe and advancing the same through the machine at a predetermined rate, means for feeding the pipe to the driving head, and means for actuating said means to feed the pipe toward the driving head at a rate faster than said first rate.

9. In a pipe wrapping machine, a driving head comprising an endless belt running longitudinally of and tractionally engaging the pipe, a conveyor for feeding pipe toward the driving head and into engagement with said belt, means for actuating the driving head belt, and means for actuating the conveyor at a rate faster than said belt.

10. In a pipe wrapping machine, a driving head comprising an endless belt running longitudinally of and tractionally engaging the pipe, a conveyor for feeding pipe toward the driving head and into engagement with said belt, means for actuating the driving head belt, means for actuating the conveyor at a rate faster than said belt, and a slip drive interposed in said last mentioned actuating means.

11. A pipe wrapping machine comprising means for applying wrapping to the pipe, means for guiding the wrapping to the pipe, and means for adjusting the position of the guide means while the wrapping is being applied to the pipe.

12. A pipe wrapping machine comprising means for applying wrapping to the pipe and at an angle with respect to the pipe axis, and means for changing said angle while the wrapping material is being applied to the pipe.

13. A pipe wrapping machine comprising a rotor, means on the rotor for applying wrapping to the pipe and at an angle with respect to the pipe axis, and means for changing said angle while the rotor is rotating.
